UNITED STATES PATENT OFFICE

2,526,887

CONTAINER FOR GREETING CARDS

George William Mack, Waterloo, Iowa

Application January 20, 1945, Serial No. 573,675

1 Claim. (Cl. 312—311)

1

This invention relates to containers, and more particularly to containers especially suitable for use as a file for greeting cards and the like. By way of example, and not by limitation, the container embodying the present invention is especially suitable for personal or individual use and is adapted to contain a plurality of different groups or types of greeting cards for various uses or purposes.

The container embodying the present invention comprises a pair of open ended box structures dimensioned and arranged so as to permit telescoping, open end into open end, one within the other, and the open end of the outer box being provided with a hinged closure member for fully enclosing the inner box within the outer box.

One of the objects of this invention is to provide a novel greeting card container which is of light weight, simple and durable construction and which is capable of being economically manufactured.

Another object is to provide an improved container of the character indicated which is of compact form adapted for convenient use, and which is constructed and arranged so as to keep the cards within the container free from dust and possible soiling or damage.

A further object is to provide an improved container of the character indicated wherein the inner box is provided with a suitable pocket on the exterior of the closed end thereof for accommodating postage stamps, labels, etc.

Still another object is to provide in a container of the character indicated, a novel arrangement of index panels disposed within the inner box structure so as to permit conveniently selecting the contents from the inner box while said box is disposed in either of the two preferred supported positions.

Other objects and advantages of the present invention will be apparent from the following description taken in connection with the following drawings in which:

Figure 1 is a perspective view of the container embodying the present invention shown in closed relation.

Figure 2 is a view similar to Figure 1 but showing the closure member in open position for permitting withdrawal of the inner box structure.

Figure 3 is a transverse sectional view through the container taken substantially as indicated at line 3—3 on Figure 1.

Figure 4 is a longitudinal sectional view through the container taken substantially as indicated at line 4—4 on Figure 1.

2

Figure 5 is a perspective view of the inner box structure shown supported on the closed end thereof with the index panels thereof in a position for conveniently selecting the contents from the box structure.

Figure 6 is a perspective view of the inner box structure supported on its bottom end with the index panels reversed end for end for conveniently selecting the contents from the inner box structure in another manner.

Figure 7 is a side elevational view of a container of slightly modified construction wherein the outer box structure has its closure member adapted to be connected by a zipper type of fastener to the body of said outer box structure.

The container embodying the present invention includes a generally rectangular outer box structure as indicated at A, and an inner box structure of generally rectangular form as indicated at B, the latter being dimensioned and arranged so as to be telescoped relatively snugly within the outer box structure. The two box structures are preferably formed of cardboard, paper board or other suitable material, so as to obtain a relatively light weight, compact construction which is capable of being economically manufactured.

The outer box structure comprises a bottom wall 10, a top wall 11, side walls 12 and an end wall 14 rigidly connected together in a manner well understood in the art. The forward end of the outer box structure is open, as clearly seen in the drawings and said opening as defined by the free edges of the top wall 11 and side walls 12, lie substantially entirely in a plane oblique to vertical. I prefer that the free edges of the sides 11 which extend at a bias, terminate at their forward edges a short distance above the bottom wall 10, as seen in the drawings.

40 Hingedly connected, as indicated at 15, to the forward free edge of the top wall 11 of the outer box structure is a closure member 16, which is formed of material similar to the body of the box structures. Said closure member includes a main, or front section 18 connected to the forward edge of a top section 19, and the opposite edge being hinged to the top 11 of the box structure body. The front section 18 and top section 19 are rigidly connected together by triangular shaped side sections 20. The closure member is so formed that in closed position it completes the general form of the box structure A, as may be clearly seen in Figure 1 of the drawings. In open position the closure member is folded upwardly and back so that the top section 19 rests upon

the top 11 of the box structure A, as clearly seen in Figure 2 of the drawings, at which time access may be had to the inner box structure B.

The inner box structure B, comprises a bottom wall 22, a top wall 23, side walls 24 and an end wall 25, all rigidly connected together. The other end of the inner box structure is open and the top wall 23 thereof, together with the side walls 24, are preferably dimensioned so that the marginal edges of the bottom, top and side walls define an opening disposed in a plane oblique to vertical as may be clearly seen in Figures 4, 5 and 6 of the drawings.

As may be clearly seen in the drawings, the inner box structure B, is telescoped into the outer box structure A, open end first, so that its closed end 25 is disposed in close proximity to the front section 18 of the closure member, when the latter is in closed position.

The closure member 16 is adapted to be securely connected in closed position and for this purpose I provide a pair of cooperating snap button fastener elements 30 and 31, mounted respectively on the inner surface of the front section of the closure member 18, and the end wall 25 of the inner box structure. To facilitate opening of the closure member and disengaging the fastener elements 30 and 31, I provide a pull tab 32 on the outer surface of the front section 18 of the closure member which preferably is attached to said member by the fastening element 33 when mounted in place on said front section 18. On the outer surface of the closed end 25 of the inner box structure, I also provide a pull tab 35 so as to permit conveniently withdrawing the inner box structure B from the outer box structure A, when the closure member 16 has been released by disengagement of the fastening element 30 from the element 31 and moved to an open position, as seen in Figure 2 of the drawings.

Mounted on the outer surface of the end wall 25 of the inner box structure is a pocket 40, in the form of an envelope, having a flap 41 which is adapted to be detachably connected to the body of the envelope by a snap fastener, as indicated at 42. The pocket is preferably dimensioned and arranged for accommodating postage stamps, labels and the like so as to make it convenient to complete the task of dispatching the greeting card after a proper card has been selected from the inner box structure as will be presently described.

The inner box structure B, is adapted to contain a plurality of index panels 50 which, as herein shown are of the same general dimensions. These panels are each provided with suitable index designations applied to the marginal ends thereof to constitute indexes for groupings and segregation of various types of greeting cards such as represented at C in Figure 4. As seen in the drawings the designation on the top panel is "Birthday-General," and is applied adjacent a pair of opposite marginal portions of the panel, and arranged so that both designations on the same panel may be readable from the same direction. The purpose of the designations appearing on the panels in such relation is to permit convenient use of the inner box structure in selecting a proper greeting card when the inner box structure is disposed in either of two positions. When it is preferred that the inner box structure be supported on its end wall 25, as seen in Figure 5 of the drawings, the index panels

are arranged as seen in Figure 5. For certain individual uses, it may be preferred that the inner box structure be supported on its bottom wall 22 as clearly seen in Figure 6 of the drawings and for such use the same set of index panels may be utilized, merely reversing them end for end within the inner box structure.

In Figure 7 of the drawings I have shown a slightly modified form of outer box structure, and more particularly a modified form of fastening means for the closure member thereof. As seen in Figure 7 of the drawings the body of the outer box structure which is indicated generally at D, has its forward or open end disposed in a plane oblique to vertical, and the closure member indicated at E, is formed and hinged to the top of the box structure D in a manner as above described. The free edges of the sides and bottom of the outer box structure and the corresponding edges of the closure member are provided with a "zipper" type of fastening means, adapted to be operated by a slide element as indicated at F, for detachably locking the closure member E in closed relation to the body of the outer box structure D in a manner well understood in the art.

Although I have herein shown and described certain preferred embodiments of my invention, manifestly it is capable of modification and rearrangement of parts without departing from the spirit and scope thereof. I do not, therefore, wish to be understood as limiting this invention to the precise embodiments herein disclosed except as I may be so limited in the appended claim. I claim:

35 A container of the character described comprising an outer box structure having rigidly connected top, bottom and side walls and an end wall, the other end of the box being open, said open end as defined by the free edges of the top wall and side walls lying substantially entirely in a plane oblique to vertical, a closure member for said open end hingedly connected to the adjacent end of the top wall and including a main front section, a connected top section adapted to constitute an extension of the top wall of the box, and side sections connecting said front section and top section to form a complete closure for said open end, an inner box structure having rigidly connected top, bottom and side walls and 50 an end wall, the other end being open to afford access to the interior of the inner box, said inner box structure being dimensioned for removably mounting, telescopically, open end first, in said outer box structure through the opening at the closure end thereof, and cooperating means on said closure member and said end wall of the inner box structure for releasably maintaining the closure member in closed relation.

GEORGE WILLIAM MACK.
